Primary Examiner — Marissa J. Cash*Assistant Examiner* — Earl B Elowsky(74) *Attorney, Agent, or Firm* — Chrisman Gallo Tochtrip LLC(57) **CLAIM**

The ornamental design for a boost tee as shown and described.

DESCRIPTION

FIG. 1 is a front perspective view of the boost tee of my new design;

FIG. 2 is an end view of one end thereof;

FIG. 3 is a plan view thereof;

FIG. 4 is a side elevation of one side thereof;

FIG. 5 is an inverted plan view thereof;

FIG. 6 is a side elevation of the other side thereof; and,

FIG. 7 is an end view of the other end thereof.

The broken lines in the drawings depict portions of the boost tee that form no part of the claimed design.

1 Claim, 4 Drawing Sheets(56)
